(57) **CLAIM**

The ornamental design for a storage container seal, as shown and described.

DESCRIPTION

FIG. 1 is a top, front and left side isometric view of a first embodiment of a storage container seal showing my new design;

FIG. 2 is a bottom, rear and left side isometric view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view, the right side being a mirror image thereof;

FIG. 8 is a cross-sectional view taken along line 8-8 of FIG. 3;

FIG. 9 is a cross-sectional view taken along line 9-9 of FIG. 3;

FIG. 10 is a top, front and left side isometric view of a second embodiment of a storage container seal showing my new design;

FIG. 11 is a bottom, rear and left side isometric view thereof;

FIG. 12 is a top plan view thereof;

FIG. 13 is a bottom plan view thereof;

FIG. 14 is a front elevation view thereof;

FIG. 15 is a rear elevation view thereof;

FIG. 16 is a left side elevation view, the right side being a mirror image thereof;

FIG. 17 is a cross-sectional view taken along line 17-17 of FIG. 12; and,

FIG. 18 is a cross-sectional view taken along line 18-18 of FIG. 12.
